CONTROL MEANS IN ABSORPTION
REFRIGERATION SYSTEM

Curtis C. Coons, Canton, Ohio, assignor to The
Hoover Company, North Canton, Ohio, a cor-
poration of Ohio

Application March 14, 1947, Serial No. 734,673

11 Claims. (Cl. 62—5)

1

This invention relates to the art of refrigeration and more particularly to a control mechanism for a dual intermittent absorption type refrigerating apparatus.

It is a principal object of the invention to provide the refrigerating apparatus of the above described character provided with a refrigeration control which is variably responsive to the demand for refrigeration, for example, to the temperature of the evaporator or of the cabinet, to regulate the operation of the dual intermittent refrigerating system.

It is a further object of the invention to provide a refrigerating system of the above described character in which a control operating in response to satisfaction of a particular refrigerating demand modifies the operation of the normal cycling control mechanism of the system to prevent the cycling control from applying heat to a generator-absorber normally next to be heated, and to allow the cycling control mechanism to operate in a normal manner to initiate heating of the absorber-generator which has previously completed its absorbing phase of operation and to initiate absorption in the generator-absorber which has previously completed its generating phase of operation when the master control responds to a demand for refrigeration.

It is a further object of the invention to provide in a system of the above described character an arrangement by which the generator which completes its generating phase of operation during a period when the refrigeration demand control has responded to a refrigeration satisfied condition is held at a low heat just sufficient to prevent re-absorption therein until the refrigeration demand control responds to a further demand for refrigeration.

Other objects and advantages of the invention will become apparent as the description proceeds when taken in connection with the accompanying drawing wherein one form of the invention is illustrated partly schematically and partly in section.

The refrigerating system as such comprises two identical intermittent refrigerating systems. Since these systems are identical in all respects with each other only one will be described. Corresponding parts of the two systems are identified by corresponding reference characters distinguished by a prime. The evaporator and liquid receiver of the left hand system are not visible in the drawing as they lie behind the identical evaporator and liquid receiver of the right hand system.

2

The left hand refrigerating system, as viewed in the drawing comprises, a generator-absorber B which is provided with a central products of combustion flue 10 surrounded by an annular jacket 11 forming with flue 10 an annular chamber for a cooling medium. An outer cylindrical member 12 forms an annular space with the cooling jacket 11 and the absorbent material is contained within in this annular space. Though my invention is applicable to various types of intermittent absorption machines, for convenience in illustration the generator-absorber structure shown here is a type particularly adapted to use a dry salt such as strontium chloride as the absorbing medium.

A conduit 14 communicates with the space between the jackets 11 and 12 and with the condenser C for the purpose of conducting refrigerant vapor from the generator to the condenser. 20 The vapor is liquified in the condenser by heat exchange with atmospheric air and the resulting refrigerant liquid is conveyed through conduit 15 to the liquid receiver R of the evaporator E. The liquid receiver R and evaporator E are not shown in the drawing as they lie behind corresponding identical elements R' and E', respectively.

If an absorbent such as water or strontium chloride is utilized in this system the refrigerant is preferably ammonia. Other refrigerant and absorbent combinations are well known to the art and may be used herein if desired.

As shown herein the evaporator E' lies against one side of a freezing chamber compartment 16 to refrigerate the same and also to refrigerate the air within the refrigerator cabinet. It will be understood that the evaporator E is similarly arranged on the opposite side of the compartment 16. The evaporator generally illustrated herein is of the type disclosed in detail in U. S. Letters Patent No. 2,379,278 issued June 26, 1945.

40 However other evaporators may be utilized if desired.

The condensers C and C' have common fins as shown in order to facilitate heat transfer and to conserve space.

45 The generator-absorber cooling system comprises the chamber formed between flue 10 and jacket 11 as heretofore mentioned. The foregoing chamber is connected to a cooling system condenser 17 by means of a conduit 18. The cooling system condensers 17 and 17' discharge into a common reservoir 19 which communicates with a control valve chamber 20 by means of a conduit 21. The control valve chamber 20 communicates with the lower ends of the cooling jacket 11

and 11' by means of conduits 22 and 22', respectively. The chamber 20 houses a valving element comprising valve plugs 24, 24' positioned to control the flow of cooling medium into the conduits 22 and 22' respectively. The valve plugs 24 and 24' are rigidly connected together by a shaft element 25. A valve actuating lever 26 is pivotally mounted in chamber 20 and has a sliding fit with the shaft 25. Springs 27 and 27' are positioned around the shaft on each side of the lever 26 so that there is a resilient driving connection between lever 26 and shaft 25 in both directions for purpose to be developed hereinafter.

Gaseous fuel burners 30, 30' are positioned to heat the boilers B and B' by discharging products of combustion through the flues 18 and 18' respectively. Fuel gas is supplied to the burner 30 from a source of supply indicated generally at 31 through a safety control pilot device 32, conduit 33, control gas valve 34 and the conduit 35. The pilot control device is of a known type in which extinguishment of the pilot flame actuates a thermostatic device to shut off all flow of gas into the system beyond the pipe 31 both to the pilot and to the burners 30 and 30'. Flash tubes 36, 35' are arranged to ignite the burners 30 and 30' from the flame of the pilot device 32.

Gas control valve 34 comprises a casing 40 formed with a valve seat 41 which is in a wall of the casing separating those parts thereof which communicate with the gas conduits 33, 35 respectively. The valve plug element 42 is positioned to seat in the opening 41 to control the flow of gas between conduits 33 and 35. The plug 42 is mounted upon an actuating shaft 43 which passes through the wall of housing 40 and is movably sealed to prevent escape of gas by a flexible diaphragm 44. A compression spring 45 engages the valve actuating shaft 43 and urges the valve plug 42 to the closed position.

A cycling control mechanism is provided to regulate the operation of the gas control valves and the cooling medium supply valve. This mechanism comprises thermostatic expansible bellows 50 and 50' which are responsive to the temperature of the boilers B and B', respectively.

The valves shafts 43, 43' are positioned in spaced relation to be engaged by a valve actuating lever 52 mounted upon a fixed pivot 53. As shown in the drawing the upper free end of lever 52 extends between the ends of the shafts 43, 43' of the valves. The lower end of lever 53 has a sliding driving connection at 54 with the valve actuating lever 26. A snap actuating arm 55 is pivotally mounted on the pivot 53 and is connected to the lever 52 by a snap spring 56. The snap acting arm 55 is positioned between the opposed thermostatic bellows 50 and 50' to be actuated thereby. Stop elements 57, 57' and 58, 58' are provided for the snap acting lever 55 and valve actuating lever 52, respectively. In addition to the above described cycling control the apparatus is provided with a refrigeration demand control which comprises a thermostatic bellows 60, shown arranged to be responsive to the temperature of the ice freezing chamber 16. This element may be responsive to the temperature within the food storage space of the refrigerator cabinet or directly responsive to the evaporator temperature as particular conditions require. The bellows 60 is mounted on a suitable fixed support 61 which may, for example but without limitation, be a portion of the interior or exterior wall of the refrigerator cabinet structure. The bellows expands and contracts against

the force of a range adjustment spring 62 which is seated against an adjusting nut and control dial device 63 for the purpose of varying the force which the compression spring 62 applies to the bellows 60. The adjusting element 63 will be mounted either inside or outside the cabinet, as the particular design may indicate as desirable, in position to be operated by the user to adjust the temperature range of the refrigerating unit.

The bellows 60 has a pivotal pin driving connection 65 with the actuating lever 66. An interrupting arm 66 pivotally mounted upon a fixed pivot 67 is arranged to be brought into and to be moved out of the path of movement of the valve actuating arm or lever 52. The lever 66 is operated by the snap actuating arm 64 by means of the snap spring 68 which connects the two.

As the bellows 60 expands indicating a demand for refrigeration, the actuating lever 66 is moved toward the position shown. As this lever passes over center the snap spring 68 actuates the arm 66 to move the same out of the path of movement of the valve actuating arm 52 after which the cycling control functions independently of the refrigeration control. When the demand for refrigeration is satisfied the bellows 60 will collapse moving the lever 66 toward its opposite position. As this lever passes over center the snap spring 68 actuates lever 66 with a snap action to move the same into the path of movement of the valve actuating arm 52. Suitable stops 69 are provided to limit the arc of movement of lever 66. The temperatures at which the bellows 60 actuates the interrupting lever 66 are varied by adjusting the adjusting dial and nut 63 to vary the bias of the spring 62 against which the bellows operates.

As illustrated in the drawing the parts are so proportioned that expansion of the bellows 50, indicating that the generator-absorber B has completed the end of a generating period, will operate the snap acting lever 55 over center and thus tend to shift the valve actuating element 52 to the right as shown in the drawing. If the bellows 60 is at this time responding to a demand for refrigeration the lever 66 will be out of the path of movement of the valve operating lever 52. Under these conditions the gas valve 41-42 will close under the bias of the spring 45. The lever 52 will open the valve 41'-42' to supply fuel to the burner 30'. Simultaneously with this operation the cooling medium control valve operating lever 26 will rotate in a counter-clockwise direction relieving tension upon the spring 27 and tensioning up spring 27' until the valve structure 24, 24' shifts to the right to shut off the flow of cooling medium into conduit 22' and to allow flow of cooling medium into the conduit 22 to begin cooling of the generator-absorber B.

When the refrigeration demand is satisfied, the bellows 60 collapses and snaps lever 66 into the path of movement of lever 52. When the above condition obtains, normal operation of the apparatus continues until the end of the generating period of operation obtaining when refrigeration demand is satisfied whereupon one of the cycling control thermostats 50-50' expands to actuate the snap acting lever 55 which in turn actuates lever 52 to the extent permitted by the lever 66. When the lever 52 is arrested by the lever 66—dotted line positions of these levers, for example—the gas valve controlling the flow of fuel to the burner associated with the generator-absorber which has just completed a generating period of operation is held in slightly open position—dotted line position of valve 42, for ex-

ample—to restrict the fuel supply to an amount just sufficient to maintain the same at a temperature high enough to prevent absorption. The gas control valve associated with the other generator absorber will however remain in fully closed position. Upon this limited movement of the lever 52 the lever 26 will move correspondingly and will relieve some of the tension upon the previously compressed spring 21 or 21' without however altering the previous position of the cooling medium control valve structure 24, 24'. This results in the following condition: One generator-absorber continues to be set up for absorbing operation; though by the time the foregoing series of events has occurred it has already absorbed substantially all the refrigerant from the evaporator. The other generator-absorber has completed a generating period of operation and is simply held in stand-by condition with a low heat input thereto to prevent absorption for the time being.

When the temperature rises and bellows 60 expands in response to the refrigerating demand and snaps the lever 66 away from engagement with the valve actuating lever 52 which then completes the movement under the bias of the spring 56 which the lever 66 previously interrupted.

In the upper portion of the figure of the drawing the evaporators, the primary and secondary condensers and their immediately associated mechanisms are shown associated with a domestic refrigerating cabinet. The evaporator structure is within the insulated food storage compartment 70 of the cabinet in the top portion thereof whereas the primary and secondary condensers C, C', and 17, 17' are positioned in an air flue 11 formed vertically along the rear wall of the cabinet structure.

The two refrigerating systems comprising the present invention should be designed to carry the maximum load condition which may reasonably be anticipated in practical use of the machine with continuous operation of the generator-absorbers under the control of the cycling control means without interruption thereof by the refrigeration demand control. If these conditions are satisfied, whatever the particular temperature setting the user may desire to place upon the adjustable control dial 63, the refrigeration demand control will occasionally interrupt operation of the cycling control at lighter loads in order to exercise control of the temperatures carried in the food storage space and/or freezing space of the refrigerating system.

It is characteristic of the illustrated form of the invention that whenever the refrigeration demand control operates the cycling control interrupting lever, the generator then operating on an absorbing phase of operation continues so to operate until it has fully absorbed the refrigerant in its associated evaporator. Similarly the generator operating on a generating phase of operation at the time the cycling control is actuated as above specified continues to operate on the generating phase of operation until the cycling control operates in response to a condition indicating that the generator has substantially discharged itself of its full complement of refrigerant vapor. The foregoing coupled with the fact that the generator which has just completed a generating period of operation is held on low heat condition throughout the period of satisfied refrigeration demand produces a situation in which a fully charged generator-absorber is

ready to be heated as soon as a fresh demand for refrigeration arises and a fully discharged generator-absorber is ready to produce its maximum refrigerating capacity as soon as the cooling medium is supplied thereto in response to a new demand for refrigeration.

The foregoing is a preferred control procedure but modifications are contemplated. For example, the low standby heat may be eliminated, this is particularly true where the generator-absorbers are well insulated as under these conditions a generator-absorber takes a long period of time to cool by radiation and no significant absorption of a refrigerant vapor will occur in any event.

15 In this type of operation the gas valve shaft 43 will be relatively short so that the valve is completely closed when the lever 52 is stopped by the lever 66. Additionally or alternately the cooling medium valve structure may be modified by making the valve plugs 24 and 24' independently movable with a lost motion connection from each to the lever 26 and springs urging the plugs to closed position so that there is a period when both valves are in closed position which coincides 20 with the position of lever 26 when lever 52 is stopped by lever 66.

25 In a general sense my invention pertains to those types of dual intermittent absorption refrigerating systems in which each system is systematically heated and cooled to generate and reabsorb refrigerant vapor respectively. In such dual systems the two systems are heated and cooled in out of phase relation with each other. The heating and cooling effect is regulated by a 30 thermostatically operated cycling control which not only heats and cools each system systematically but also heats and cools the two systems in out of phase relation with each other according to some pre-determined schedule of operations.

35 40 It is particularly characteristic of the present invention that the refrigerant control modifies the operation of the cycling control to prevent it from applying heat to a system which was not last heated in the normal schedule of operations of the cycling control.

45 I claim:

1. In a refrigerating apparatus, a pair of intermittent refrigerating systems each including a generator-absorber, a condenser and an evaporator connected in circuit; means for cooling said generator-absorbers, means for heating said generator-absorbers, a cycling control for operating said heating means and said cooling means to heat and cool each of said generator-absorbers alternately in out of phase relationship to each other, said cycling control means including a member movable from a first position in which one of said generator-absorbers is heated and the other generator-absorber is cooled through an intermediate range of movement in which neither generator-absorber is heated to a second position in which said one generator-absorber is cooled and said other generator-absorber is heated, a refrigeration demand control including a member movable into and out of the path of movement of said first member to interrupt movement thereof prior to the point at which heat is applied to a previously cooled generator-absorber and cooling medium is applied to a previously heated generator-absorber.

2. In a refrigerating apparatus, a pair of intermittent refrigerating systems each including a generator-absorber, a condenser and an evaporator connected in circuit; a gas burner arranged 50 to heat each of said generator-absorbers, a gas

valve having high and low heat and off positions arranged to govern the flow of gas to each of said burners, a cooling system charged with a cooling medium having a heat absorbing part in heat exchange relation with each of said generator-absorbers, a control valve structure in said cooling system arranged to direct cooling medium into a selected one of said heat absorbing parts, actuating mechanism associated with said gas valves and said cooling medium flow control valve arranged to heat and cool said generator-absorbers alternately in out of phase relation by moving the gas valve controlling the gas burner associated with one generator-absorber to the high heat position and moving the cooling medium valve to supply cooling medium to the heat absorbing part associated with the other generator-absorber, refrigeration control means including a member shiftable into position to arrest operation of said actuating mechanism as it is operating to reverse the application of heat and cooling medium to said generator-absorbers at a point at which the cooling medium control valve has not been operated and the gas valve previously held in high heat position has been operated to the low heat position.

3. Refrigerating apparatus including a pair of intermittent absorption refrigerating systems of the type which are successively heated and cooled in operation, means for heating and cooling said systems, means for governing the operation of said heating and cooling means, thermostatic cycling control means responsive to the thermal condition of portions of said systems including a snap actuating lever operated by said thermostatic means, an operating lever connected to be actuated by said snap actuating lever by means of a snap spring, said operating lever being arranged to operate said governing means to heat and cool each of said systems successively and in out of phase relation with each other, refrigeration demand responsive thermostatic means, an interrupting lever connected to be operated by said refrigeration demand responsive means and mounted to be moved into the path of movement of said operating lever by said refrigeration demand responsive means when the refrigeration demand is satisfied, said interrupting lever being so mounted with respect to said operating lever that said operating lever is moved into engagement therewith by the bias of said snap spring after said cycling control means has operated said snap actuating lever to discontinue heating of one of said systems, and said operating lever is stopped by said interrupting lever against the bias of said snap spring before it has operated said governing means to initiate heating of the refrigerating system next to be heated.

4. Refrigerating apparatus including a pair of intermittent absorption refrigerating systems of the type which are successively heated and cooled in operation, means for heating said systems, means for regulating said heating means to apply heat at a high generating rate or a low standby rate to said refrigerating systems, means for cooling said refrigerating systems by passing a cooling medium in heat exchange relation therewith, means for governing the operation of said cooling means to control the flow of cooling medium, cycling control means normally automatically operable to actuate said regulating means and said governing means to apply a high generating heat and cooling medium to each of said systems successively and in out of phase relation with each other, and refrigeration control

means operable when the demand for refrigeration is satisfied to modify the normal operation of said cycling control means to cause said cycling control means to reduce the heat to the system operating on its generating period of operation to a low standby heat at the end of its generating period of operation without initiating cooling thereof.

5. Refrigerating apparatus including a pair of 10 intermittent absorption refrigerating systems of the type which are successively heated and cooled in operation, means for heating and cooling said systems, and mechanism governing said heating and cooling means to control the production of refrigeration by said systems including refrigeration demand responsive control means, means for operating said heating and cooling means to heat and cool each of said systems successively and in out of phase relation with each other, when 15 said refrigeration demand responsive means is responding to a demand for refrigeration, and means for heating one of said systems with a low standby heat at the end of a normal heating period thereof and for barring cooling of said one 20 system when said refrigeration demand responsive means responds to a refrigeration demand satisfied condition.

6. Refrigerating apparatus including a pair of 25 intermittent absorption refrigerating systems of the type which are successively heated and cooled in operation, means for heating and cooling said systems, control means for controlling the operation of said systems including means for regulating said heating means, means for governing said 30 cooling means, a cycling control means including means for operating said regulating means and said governing means to heat and cool each of said systems successively and in out of phase relation with each other, and refrigeration demand responsive means operable when refrigeration demand is satisfied to continue heating the previously heated system at a low standby heat rate and to prevent the application of heat to the other system.

45 7. Refrigerating apparatus comprising a generator-absorber, a condenser and an evaporator connected in circuit; means for heating said generator-absorber to operate the same on a generating period of operation, means for cooling said generator-absorber to operate the same on an absorbing period of operation, a movable member for operating said heating means and said cooling means for heating and cooling said generator-absorber successively, an energy storing and releasing means arranged to release stored 50 energy to operate said movable member, cycling control means for storing energy in said energy storing means for shifting said generator-absorber from generating phase to absorbing phase operation and vice versa, and refrigeration demand control means operable so long as refrigeration demand is satisfied to arrest operating movement of said member against the bias of said energy storing means to prevent initiation of a period 55 of operation of said generator-absorber opposite in phase to the immediately preceding period of operation.

8. Refrigerating apparatus including a pair of 60 intermittent absorption refrigerating systems of the type including parts which are successively heated and cooled in operation, means for heating and cooling said parts, means for governing the operation of said heating and cooling means, cycling control means for operating said governing 65 means to heat and cool each of said systems

successively and in out of phase relation with each other and refrigeration demand responsive means operable in response to a refrigeration demand satisfied condition to alter the operation of said cycling control means as it is operating to reverse the application of heat and cooling medium to said generator-absorbers to reduce the heat to the heated part of the generating generator-absorber to a low standby heat rate just sufficient to maintain the heated generator-absorber above an absorbing temperature and to lock said cycling control means against operating said governing means to supply cooling medium to said generator-absorber.

9. Refrigerating apparatus comprising; a generator-absorber, a condenser and an evaporator connected in circuit; means for heating said generator-absorber; means for cooling said generator-absorber; and means for controlling the operation of said heating means and said cooling means including, a member movable from a first position in which said heating means is activated through a second position in which said heating means and said cooling means are inactive to a third position in which said cooling means is active, means responsive to the temperature of said generator-absorber for operating said movable member to activate said heating means and said cooling means successively, and refrigeration demand responsive means operable in response to a refrigeration demand satisfied condition for arresting said movable member in said third position when moved thereto by said operating means.

10. Refrigerating apparatus including; a pair of intermittent absorption refrigerating systems each including a part which is successively heated and cooled in operation; means for heating said parts; means for cooling said parts; and means for controlling the operation of said heating means and said cooling means including, a member movable from a first position in which said heating means is activated to heat one of said parts and said cooling means is activated to cool the other of said parts through a second position in which said heating means is de-activated to a third position in which said heating means is activated to heat said other part and said cooling means is activated to cool said one part, means responsive to the temperature of said parts for operating said movable member to activate said heating means and said cooling means to heat and cool each of said parts successively in out of

phase relation to each other, and refrigeration demand responsive means operable in response to a refrigeration demand satisfied condition for arresting said movable member in said third position when moved thereto by said operating means.

11. In a control mechanism for a dual intermittent absorption refrigerating apparatus of the type including, a pair of elements which are alternately heated and cooled in out of phase relation, means for heating said elements, and means for cooling said elements; means for controlling the operation of said heating means and said cooling means including, a member movable from a first position in which said heating means is activated to heat one of said elements and said cooling means is activated to cool the other of said elements through a second position in which said heating means is de-activated to a third position in which said heating means is activated to heat said other element and said cooling means is activated to cool said one element, means responsive to the temperature of each of said elements when heated to a predetermined temperature for operating said movable member to activate said heating means and said cooling means to heat and cool said elements successively in out of phase relation to each other, a stop means movable into an operating position in which it engages and stops said movable member in said third position when moved thereto by said operating means, means biasing said stop means to an inoperative position, and refrigeration demand responsive means for moving said stop to said operative position when refrigeration demand is satisfied and for holding said stop in said operative position as long as refrigeration is satisfied.
